COMBINED CURTAIN POLE AND SHADE SUPPORT

Filed June 6, 1931

UNITED STATES PATENT OFFICE

FREDERICK J. ROCK, OF SYRACUSE, NEW YORK

COMBINED CURTAIN POLE AND SHADE SUPPORT

Application filed June 6, 1931. Serial No. 542,598.

My invention relates to lace curtain and shade fixtures, and it consists in the construction, arrangements and combinations herein described and claimed.

It is an object of my invention to provide a fixture mounting in which brackets for support of lace curtains and a shade are embodied upon single mounting plates, thus greatly facilitating the installation of shades and curtains upon a window.

It is a further object of the invention to provide a fixture in which the curtain and shade brackets are adjustable to accommodate draperies of varying widths and to also provide means in the curtain brackets for vertical adjustment thereof.

A still further object of the invention is the provision of fixtures which may be cheaply manufactured, readily installed upon a window frame and give a neat and attractive appearance.

Additional objects, advantages and features of invention will be apparent from the following description and accompanying drawings, wherein:

Figure 1 is a fragmentary elevation of a window frame having my brackets in place, and illustrating the shade and curtain rods in position:

Fig. 2 is a cross section on the line 2—2 of Fig. 1;

Fig. 3 is a cross section on the line 3—3 of Fig. 1;

Fig. 4 is a detail perspective view of one of the brackets.

My brackets may be applied to any window frame, and for the sake of illustration I have shown a conventional construction of framing 10, the upper corner portions of which are recessed as at 11, within which my brackets 12 are secured by screw fastenings as at 13.

The brackets 12 which are disposed upon opposite sides of the frame, are identical in construction, and therefore a detailed description of only one will be made.

The bracket 12 comprises a mounting plate 14 which has a circumscribing flange 15 of a depth to seat within the recess 13 and posi-

tion the plate 14 flush with the exterior surface of the frame 10.

A pair of slots 16 and 17 are formed in the plate 14 lying in parallel planes, the lower slot 16 extending from a point closely adjacent one vertical edge of the plate to a point beyond a vertical center of the plate, and the upper slot 17 is similarly formed, but extends from the opposite vertical edge of the plate.

Within the slot 16 there is provided a shade bracket 18 which in the present instance comprises a rectangular plate 19 adapted to lie flush against the plate 14 and of a width to project beyond the edges of the slot 16. A pin 20 carried by the plate 19 is extended through the slot 16 and has a head 21 for maintaining the plate 19 in sliding relation with the plate 14.

The bracket 18 has a shade supporting arm 22 extended at right angles to the plate 19 which has a suitable slot or aperture 23 for reception of the trunnions 24 of a roller shade 25.

In order to obtain various adjustments of the bracket 18 upon the bracket plate 14, the plate 19 is apertured to receive a threaded bolt 26, the shank portion of which is slidable within the slot 16. A wing nut 27, engaged upon the bolt 26 is employed for securing the bracket 18 in adjusted positions upon the plate 12, as readily understood.

Within the upper slot 17, a U-shaped support 28 is adjustably secured, this securement being provided by a threaded bolt 29 extended through the slot 17 and through a suitable aperture formed medially of the body 30 of the support, as clearly shown in Fig. 2. The clamping action between the bracket plate 14 and the support 28 is obtained by tightening of the wing nut 31. The support 28 comprises a pair of arms 32 and 32^a extended at right angles to the body 30 for support of curtain rods 33.

The curtain rods 33 are of the extensible type formed of sheet metal and bent and shaped to engage telescopically over the arms 32 and 32^a as most clearly shown in Fig. 3.

It will be apparent that by loosening the wing nut 31, the support 28 may be adjusted

to any desired position within the slot 17, and that by tightening the nut, such adjustment will be retained.

6 The arms 32 of opposite brackets may support a rod 33 from which a curtain may be suspended, while the arms 32^a may include a rod 33 so shaped as to suspend a usual curtain cap or other drapery.

10 Occasion may arise where it would be desirable to support a plurality of curtains, cap members or the like, and this may be carried out by providing an auxiliary bracket 34.

15 The bracket 34 includes an upright 35, vertically slotted at its lower end, as at 36, and upon its upper end there is suitably secured, as by welding, a horizontally disposed member 37, having right angularly disposed arms 38, 39 and 40. The bracket 34 is secured to the bracket 28 by positioning the upright 35 between the body portion 30 and the wing nut 31, the bolt 29 being disposed within the slot 36. Thus, the bracket 34 may be adjusted vertically with respect to the bracket 28 and by tightening the wing nut 31, such adjustment will be maintained.

20 26 As clearly shown in Fig. 4, the arms 38, 39 and 40 support respective curtain rods 41, 42 and 43, and in such relation as to suspend the curtains, caps or the like in superposed position.

30 35 While I have shown and described a preferred form of my invention I do not limit my invention thereto, and retain as my own all such modifications as fairly fall within the scope of the appended claims.

What I claim is:

40 1. A combined shade and curtain support comprising a mounting plate having slots, curtain and shade brackets horizontally adjustable within said slots, a second curtain bracket carried by said first named curtain bracket and vertically adjustable thereon, and clamping means for securing said brackets in various adjusted positions.

45 2. A combined curtain and shade support comprising a mounting plate, a shade bracket adjustably mounted thereon, a curtain bracket adjustably mounted upon said mounting plate, said bracket having a pair of laterally extended arm members for support of curtain rods, a second curtain bracket adjustably related to said first named curtain bracket and having arms for support of curtain rods, and a single clamp means for securing said curtain brackets in adjusted relation.

50 60 3. A combined curtain and shade support comprising a mounting plate, a shade bracket, a curtain bracket laterally adjustable upon said mounting plate, a second curtain bracket vertically adjustable to said first named curtain bracket, and a single clamp means for securing said curtain brackets in adjusted relation.

65 4. A combined curtain and shade support

comprising a mounting plate, a shade bracket, a curtain bracket laterally adjustable upon said mounting plate, and having a pair of arms for support of curtain rods, a second curtain bracket vertically adjustable to said first named curtain bracket and having a plurality of curtain rod supporting arms, and a clamp bolt operatively associated with said curtain brackets.
